UNITED STATES PATENT OFFICE.

WALTER H. KNIGHT, OF NEW YORK, N. Y.

ELECTRIC RAILWAY.

SPECIFICATION forming part of Letters Patent No. 338,083, dated March 16, 1886.

Application filed July 10, 1885. Serial No. 171,189. (No model.)

To all whom it may concern:

Be it known that I, WALTER H. KNIGHT, a citizen of the United States, and a resident of New York, N. Y., have invented certain new and useful Improvements in Electric Railways, of which the following is a specification.

My invention consists in certain devices whereby, in an electric railway having one or both of its main conductors inclosed in a slotted conduit, a contact device extending through the slot to the said conductors may be guided into either one of two branch railways.

In the accompanying drawings, Figure 1 represents a plan of an electric railway at the point of branching, showing the track-rails and the conduit-slot. Fig. 2 is a section of the same on the line 2 2 of Fig. 1. Fig. 3 shows in detail the actuating mechanism for the slot-switching point. Fig. 4 represents the conductors at the branching point.

In Fig. 1, A and B are the two main conductors, shown by dotted lines as inclosed in the conduit, having its slot represented by S. A' B' are the corresponding conductors in one branch, and A² B² are the corresponding conductors in the other branch.

A contact device consisting of the plow P and contact-shoes m m', of the construction shown in a patent granted to me September 23, 1884, and numbered 305,731, is represented in Fig. 1.

At the branching point of the slot is pivoted a point, C, which is adapted to be turned to one side or the other, so as to close one branch slot and leave the other branch slot open as a continuation of the main slot. By means of this point C the plow P may be directed into either branch conduit. The plow P being deflected into either branch, the contact-shoes m m' will go with it into the same branch.

As shown in Fig. 4, the branch conductor A² is connected to the main conductor A, and the branch conductor B' is connected correspondingly to the main conductor B, while A' and B² form continuations of A and B, respectively. The contact-shoes m m' are adapted to bear upon the vertical surfaces of the main conductors, and when deflected into either branch will necessarily pass between one of the branch conductors, as B', and its corresponding main conductor B, so that the wire

connecting B' and B must be placed out of the line of the progress of the contact-shoes.

In order that the slot-point C may always be turned correspondingly with the track-switching point, I connect the two together, so that they can only be moved simultaneously. This is done by the mechanism illustrated in Figs. 2 and 3.

D represents an upright post journaled in the top and bottom plates of the conduit, and carrying at its upper end the slot switching point C. A connecting-rod, E, is fastened to D, and extends back from it horizontally. To the end of E is pivoted a rod, F, having its opposite end pivoted to lever G. Lever G has also a connection, H, with the track switching point e, and an operating-lever, K, is pivoted with a connecting-rod between it and H, so that when K is turned to one side or the other both the slot-switching point and the track-switching point will be thrown into the corresponding position.

The slot-switching point C rests upon the top plate of the conduit, so that its extreme end is constantly upheld by the edge of the slot, while if upheld from beneath the support would interfere with the insulated conductors inclosed in the slot.

The conductors, it will be observed, are stationary at the branching-point and not movable, as is usually the case in switches for electric railways.

Having thus described my invention, what I claim is—

1. The combination, in a branching electric railway, of a track-switch, a branching slotted conduit having a movable guide-piece at the branching-point and contact devices extending into said slot, main conductor A, branch conductor A', forming a continuation of A, and a branch conductor, A², connected electrically to A and A', but so placed as to allow passage of the contact device between itself and said conductors A A'.

2. The combination, in an electric railway, of a branching slotted conduit parallel therewith, an electric conductor in main and branch conduit stationary at the branching point, contact devices extending into said conduit through the slot to connect with said conductor, a track-switch, and a movable guide-piece for said slot at the point of branching.

3. The combination, with the branching slotted conduit, of an insulated electric conductor inclosed therein and supported in position to be reached by a contact device, and a movable 5 guide-piece for the slot at the point of branching resting upon the surface of said conduit and supported thereby.

4. The combination of the branching slotted conduit, the contact device extending into it, 10 the conductor stationary at the branching-

point, and the movable guide for said contact devices at the branching-point of the slot.

In testimony whereof I sign this specification, in the presence of two witnesses, this 30th day of June, 1885.

WALTER H. KNIGHT.
